UNITED STATES PATENT OFFICE.

KARL ARNSTEIN, OF FRIEDRICHSHAFEN, BODENSEE, GERMANY, ASSIGNOR TO LUFTSCHIFFBAU ZEPPELIN GESELLSCHAFT MIT BESCHRANKTER HAFTUNG, OF FRIEDRICHSHAFEN, BODENSEE, GERMANY.

STERN CONSTRUCTION OF RIGID AIRSHIPS.

Application filed September 4, 1924. Serial No. 735,842.

To all whom it may concern:

Be it known that I, KARL ARNSTEIN, a citizen of Czechoslovakia, and a resident of Friedrichshafen, Bodensee, Germany, have invented certain new and useful Improvements in Stern Constructions of Rigid Airships, of which the following is a specification.

My invention relates to a way of reinforcing the stern of rigid airships especially in connection with fins.

It has for some time been usual to construct the four fins of a rigid airship, serving for stabilizing the ship, without external bracing, giving them a triangular cross section. These bodily fins are rigidly connected to the hull of the ship which is made up of longitudinal members and cross members—the latter called rings.

According to my invention the girders or ribs of the fins at those cross sections of the ship where there is a ring are carried right through this ring to the opposite ring corners there joining the girders or ribs of the opposite situated fin. Usually there are four fins placed at the ship's stern and therefore according to my invention the rings in the stern will be intersected by two pairs of girders connecting the ring corners where the fin ribs join. At the points of intersection of these girders they are connected together and the panels which are formed by the ring girders and reinforcing girders are braced so as to constitute together with the ring a kind of circular truss. Thereby a perfect reinforcement of the ship's stern is attained making certain a secure way of transmitting the air stresses from the fins to the hull structure. It is of the highest importance to have a safe construction in the ship's stern where the stresses on the fins and on the rudders and elevators attached to them may vary greatly in strength as well as direction.

Having given a general explanation of my invention I now want to point out the details thereof referring to the drawing giving an example embodying my invention.

In the drawing Fig. 1 is a side view showing the construction of the ship's stern and giving in dotted lines the outer shape of the fins, rudders and elevators; Fig. 2 is a cross section taken on line 2—2 of Fig. 1, and Fig. 3 is a cross section taken on line 3—3 of Fig.

1. So is Fig. 4, only another way of staying the ring is represented. 55

In Fig. 1 the outline of the horizontal fin is designated by the letter *a* and that of the elevator by *b*. The letter *c* represents the outlines of the vertical fin and *d* are the rudders. The contour of the ship's stern is designated by *e*. The two cross members of the hull (or rings) are marked *f*¹ and *f*². The ribs situated in the same plane with these rings are designated by *g*.

In Fig. 2 ring *f*¹ is shown with the four 65 fins attached to it according to my invention. Fig. 3 shows ring *f*² with the same details as shown with Fig. 2. The ribs of the fins are designated by *g*¹ to *g*⁸ respectively. Ribs *g*¹ and *g*² are connected to ribs *g*³ and *g*⁴ by 70 means of girders *h*¹, *i*¹, *h*³ and *h*², *i*², *h*⁴, respectively. In the same way ribs *g*⁷ and *g*⁸ are connected to ribs *g*⁵ and *g*⁶ by girders *h*⁵, *i*¹, *h*⁷ and *h*⁶, *i*², *h*⁸, respectively. The 75 panels formed by the intersecting girders are stayed by braces *k*. The bearings for the rudders and elevators are designated by *l*¹ and *l*².

In Fig. 4 another example is given showing how the reinforcement of the ring by 80 means of girders may be attained. Here the ribs of the fins are not connected with those directly opposite but the ribs of adjacent fins are connected by girders as *p*¹ and *p*², which cross each other. The point of intersection 85 of these two girders is connected with the adjacent ring corner by a girder *r*. The ring truss thus created is stayed by wires *g*.

I want it understood that I do not limit myself to the example described and shown 90 in the drawing as many variations will occur to persons skilled in the art.

Claims:

1. An airship of the rigid type, comprising a hull made up of longitudinal members 95 and ring members, horizontal and vertical fins situated in the ship's stern, the ribs of said fins that are situated in the plane of a ring being connected to each other by reinforcing girders situated within said ring. 100

2. An airship of the rigid type, comprising a hull made up of longitudinal members and ring members, horizontal and vertical fins situated in the ship's stern, the ribs of said fins that are situated in the plane of a 105 ring being connected to each other by rein-

forcing girders situated within said ring, said girders being connected to each other at their points of intersection.

3. An airship of the rigid type, comprising a hull made up of longitudinal members and ring members, horizontal and vertical fins situated in the ship's stern, the ribs of

said fins that are situated in the plane of a ring being connected to each other by reinforcing girders situated within said ring, 10 said girders being connected to each other at their points of intersection, said points of intersection being braced by tension members.

KARL ARNSTEIN.
